A. R. BABCOCK

Des. 100,192

NONREPEATING INDICATOR

Filed April 30, 1936

FIG. 1.

FIG. 2.

Inventor:

Alfred R. Babcock
Baldyrenforth, Lee, Chittom, Miles
Attn:

UNITED STATES PATENT OFFICE

100,192

DESIGN FOR A NONREPEATING INDICATOR

Alfred R. Babcock, Chicago, Ill.

Application April 30, 1936, Serial No. 62,390

Term of patent 7 years

To all whom it may concern:

Be it known that I, Alfred R. Babcock, a citizen of the United States, residing at Chicago, county of Cook and State of Illinois, have invented a new, original, and ornamental Design for a Non-Repeating Indicator, of which the following is a specification, reference being had to the accompanying drawing, forming a part thereof, in which:

Figure 1 is a side elevational view of a non-repeating indicator embodying the invention; and Fig. 2, a front elevational view of the same.

I claim:

The ornamental design for a non-repeating indicator, as shown.

ALFRED R. BABCOCK.
